UNITED STATES PATENT OFFICE.

EDGAR G. TAGUE, OF INDIANAPOLIS, INDIANA.

COMBINED BEVEL AND SQUARE.

SPECIFICATION forming part of Letters Patent No. 761,336, dated May 31, 1904.

Application filed April 2, 1904. Serial No. 201,278. (No model.)

To all whom it may concern:

Be it known that I, EDGAR G. TAGUE, a citizen of the United States, residing at Indianapolis, in the county of Marion and State of Indiana, have invented new and useful Improvements in a Combined Bevel and Square, of which the following is a specification.

My invention pertains to measuring instruments of the bevel type, and contemplates the provision of a combined bevel and T-square, which is calculated to facilitate the finding of angles and is therefore adapted to be used to advantage in framing roofs.

With the foregoing in mind the invention will be fully understood from the following description and claims when taken in connection with the accompanying drawings, forming part of this specification, in which—

Figure 1 is a side elevation of the instrument constituting the present and preferred embodiment of my invention as the same appears when its arms are fully extended. Fig. 2 is a similar view of the instrument as it appears when folded—*i. e.*, when the arms are swung into the body. Fig. 3 is a longitudinal central section of the instrument, taken in the plane indicated by the line 3 3 of Fig. 2. Fig. 4 is a transverse section, on an enlarged scale, taken in the plane indicated by the line 4 4 of Fig. 2; and Fig. 5 is a perspective view, on an enlarged scale, of one of the slides of the instrument removed.

Similar letters of reference designate corresponding parts in all of the several views of the drawings.

In the present and preferred embodiment of my invention the combined bevel and T-square comprises a body A, preferably of steel or other suitable metal, arms B, also preferably of steel or other suitable metal, having reduced and lapped inner ends *a*, pivotally connected at *b* to the body, slides C, movable independently of each other in the body and in the direction of the length thereof, links D, pivotally connected to the arms B, and bolts E and wing-nuts F, through the medium of which the links are pivotally connected to the slides. As best shown in Figs. 3 and 4 of the drawings, the body A is made up of walls *c*,

connected together in such manner as to afford a space *d* between them and having slots *e* disposed at right angles to said space and also having recesses *g* in their outer sides. On the bottoms of the said recesses graduated scales *f* are provided, as clearly shown in Figs. 55 1 and 2, one of the said scales and its complementary slide C and arm B being designed for use in determining the rise to foot and the other scale and its complementary slide C and arm B being for use in the making of 60 jacks and hip-cuts. The slides C are movable on the bottoms of the recesses *g* and in the direction of the length of the body and are provided with reduced inner portions *h*, disposed in the slots *e* of the body. The bolts 65 E, which pivotally connect the links D to the slides C, extend loosely through the slides, Fig. 4, and are threaded at their outer ends to receive the wing-nuts F. These latter bear against the outer sides of the slides and are 70 arranged entirely within the recesses *g* of the body, this in order to prevent them from interfering with the manipulation of the body when the same is laid flat on a surface.

In virtue of the construction of my novel 75 bevel and T-square it will be observed that the arms B may be moved independently of each other with their complementary links D and slides C, and by the use of the slides, in conjunction with the graduated scales *f*, various angles may be found and the framing of 80 roofs and similar work thereby materially facilitated. It will also be observed that in order to fix the arms B with respect to the body it is simply necessary to set the wing- 85 nuts F against the faces of the slides C, so as clamp the slides against the body.

I have entered into a detailed description of the construction and relative arrangement of the parts embraced in the present and preferred embodiment of my invention in order to impart a full, clear, and exact understanding of the same. I do not desire, however, to be understood as confining myself to such specific construction and relative arrangement of parts, as such changes or modifications may be made in practice as fairly fall within the scope of my invention as claimed. 95

Having described my invention, what I claim, and desire to secure by Letters Patent, is—

1. In an instrument of the character described, the combination of a body provided with graduated scales, arms pivotally connected to the body and movable independently of each other, slides movable on the body, and adapted to be used in conjunction with the graduated scales, and links interposed between and connecting the arms and the slides.
2. In a combined bevel and T-square, the combination of a body provided at its opposite sides with graduated scales, arms pivotally connected to the body at one end thereof, and arranged to be opened to positions at right angles to the body, and also arranged to move independently of each other, slides movable on the body and adapted to be used in conjunction with the graduated scales; and links interposed between and connecting the arms and the slides.
3. In an instrument of the character described, the combination of a body having a recess g in one side, an arm pivotally connected to the body, a slide movable in the recess of the body, a link pivotally connected to the

arm, a bolt connecting the link and the slide and threaded at its outer end, and a nut mounted on said threaded end of the bolt and arranged entirely within the recess of the body.

4. In an instrument of the character described, the combination with a body having a space d and slots e disposed at right angles to the said space d , and also having recesses g in its opposite sides, and graduated scales on the bottoms of said recesses, arms pivotally connected to the body at one end thereof and movable independently of each other, and adapted to take into the space d of the body, slides movable in the recesses g of the body, links pivotally connected to the arms, bolts connecting said links and the slides and threaded at their outer ends, and nuts mounted on said threaded ends of the bolts and arranged entirely within the recesses g of the body.

In testimony whereof I have hereunto set my hand in presence of two subscribing witnesses.

EDGAR G. TAGUE.
